[57] CLAIM

The ornamental design for a phonograph record display frame or similar article, as shown and described.

DESCRIPTION

FIG. 1 is a view in perspective as seen from the top, front and one side of a phonograph record display frame or similar article showing my new design;

FIG. 2 is a view in side elevation thereof, the side opposite being a mirror image;

FIG. 3 is a front elevation thereof;

FIG. 4 is a rear elevation thereof;

FIG. 5 is a view in top plan thereof, the bottom plan being a mirror image; and

FIG. 6 is a cross sectional view taken along line 6—6 of FIG. 3.

The broken line showing of a record in FIG. 1 is for illustrative purposes only and forms no part of the claimed design.
